UNITED STATES PATENT OFFICE.

ERNEST MARRIOTT BARKER, OF ST. LEONARDS-ON-SEA, ENGLAND.

CARBURETER.

981,156.

Specification of Letters Patent. Patented Jan. 10, 1911.

Application filed June 22, 1909. Serial No. 503,748.

To all whom it may concern:

Be it known that I, ERNEST MARRIOTT BARKER, M. B., of Winstowe, Charles Road, St. Leonards-on-Sea, in the county of Sussex, England, have invented certain new and useful Improvements in and Relating to Carbureters for Internal-Combustion Engines, of which the following is a specification.

10 This invention has reference to improvements in and relating to carbureters for internal combustion engines and has for its object to provide an improved construction thereof, whereby greater economy and efficiency than heretofore in the consumption of the fuel is obtained.

The invention relates particularly to carbureters of the kind in which the combustion air drawn by the motor consists of two portions, whereof one (primary air) is led past the fuel nozzle to form a rich mixture, whereas the other portion (secondary air) is led into the mixture to dilute and complete the same.

25 The characteristic feature of the invention consists in the arrangement of a fine horizontal fuel nozzle over and opposite the restricted orifice of a vertical primary air tube and close to a baffle disposed in a concentric secondary air tube or passage, whereby the secondary air is deflected to form a low pressure zone over said baffle under the suction of the motor, so that a vertical pencil of primary air meets a fine pencil of petrol at 30 right angles in the said low pressure zone. By this means the pencil of primary air at once atomizes and vaporizes the petrol, and the further advantage is attained that the fuel can be kept at a very low level beneath 35 the nozzle, so that flooding at starting and during running is prevented and this without unduly choking the engine.

The accompanying drawings show a carbureter made in accordance with this invention.

45 Figure 1 is a sectional elevation of the carbureter. Fig. 2 is a plan thereof. Fig. 3 is an elevation of the cap *h*, and Fig. 4 is a plan thereof.

50 The fuel nozzle *a* is supplied by a pipe *b* leading to a supply of spirit or oil. This pipe extends through a mixing chamber *c* connected to the inlet pipe of the engine, and the nozzle *a* projects horizontally through a 55 cap *h* so as to discharge the fuel into the path of a pencil of primary air induced

through an air nozzle *e* by the suction of the engine. The secondary or diverted air current is induced through a flue *d* surrounding the primary air nozzle *e* and is deflected by 60 a baffle *f* at the top. A plug *g* allows of obtaining access to the fuel nozzle for cleaning or other purpose. The cap *h* automatically adjusts the quantity of the air admitted by the flue *d*. It is provided with ports *k* and 65 a flange *j* whose inner edge is configurate with but slightly larger than the outer edge of the baffle *f*. The air supply to the flue *d* may be heated in any well-known manner.

In operation, the suction of the engine 70 causes a flow of secondary air through the air flue *d* and a jet of primary air through the air nozzle *e*. The baffle *f* at the upper orifice of the air flue *d* diverts the air current passing through *d* and creates a zone 75 of low air pressure over the upper surface of the baffle plate. The jet of air induced through the nozzle *e* and the jet of fuel induced through the nozzle *a* are delivered into the heart of this low pressure zone and meet 80 each other at right angles, with the result that the fuel is perfectly atomized and vaporized and a very powerful suction created on the fuel, enabling the carbureter to start and work with the fuel at a level considerably below that of the fuel nozzle. The suction on the fuel jet is regulated according to the pressure existing in the low pressure zone. Thus when the supply of combustible mixture from the mixing chamber is throt- 85 tled for running the engine slowly, the cap *h* rests on the air flue, thereby throttling the inlet; the initial supply of fuel will therefore be small, consequent on there being no pronounced low pressure zone above the 90 baffle; when running at high speed the suction of the engine induces a greater rush of air through the air flue *d* thereby making the low pressure zone above this baffle more pronounced and also forcing up the cap *h*, 95 so that more air is admitted to the mixing chamber from beneath the flange *j* and through the ports *k*. The pressure of the lower pressure zone is thereby reduced and the supply of fuel through the nozzle is more 100 rapid.

What I claim is:—

1. A carbureter comprising in combination a vertical primary air tube having a restricted outlet, a vertical secondary air conduit surrounding said primary air tube, a fine horizontal liquid fuel nozzle disposed 110

over with its outlet opposite and close to said restricted orifice, and a baffle located at the outlet end of the secondary air conduit and immediately below the extremity of the fuel nozzle, whereby to divert the secondary air current and thereby form a low pressure zone around the impinging point of the jets of primary air and fuel.

2. A carbureter comprising the combination of a mixing chamber, a nozzle for supplying the fuel, a flue for conveying secondary air to the mixing chamber, a baffle in the air flue, an air nozzle disposed approxi-

mately at right angles to the fuel nozzle, said air nozzle and fuel nozzle being in close proximity to the baffle and juxtaposed and a cap over the air flue adapted to be moved by the flow of air to vary the opening between said flue and chamber.

In witness whereof, I have hereunto signed my name in the presence of two subscribing witnesses.

ERNEST MARRIOTT BARKER.
